UNITED STATES PATENT OFFICE

141,059

DESIGN FOR A TRANSPARENT PHOTOGRAPH HOLDER

Fred Siegel, New York, N. Y.

Application July 17, 1944, Serial No. 114,435

Term of patent 7 years

(Cl. D29—20)

To all whom it may concern:

Be it known that I, Fred Siegel, a citizen of the United States, residing at New York, county and State of New York, have invented a new, original, and ornamental Design for a Transparent Photograph Holder, of which the following is a specification, reference being had to the accompanying drawing, forming a part thereof.

Fig. 1 is a vertical perspective view of a photograph holder, showing my new design;

Fig. 2 is an end view corresponding to Fig. 1; Fig. 3 is a perspective view of the frame in horizontal position; and

Fig. 4 is an end view corresponding to Fig. 3.

I claim:

The ornamental design for a transparent photograph holder, as shown.

FRED SIEGEL.
